United States Patent Office

Des. 192,943
Patented May 29, 1962

192,943

FOOD CONTAINER OR THE LIKE

Clara Virginia Eicholtz, Midland, Mich., assignor to The Dow Chemical Company, Midland, Mich., a corporation of Delaware

Filed Dec. 5, 1960, Ser. No. 63,095

Term of patent 14 years

(Cl. D58—25)

Fig. 2

Fig. 3

Fig. 1

Fig. 4

Fig. 5

FIGURE 1 is an elevational view of a food container or the like showing my new design;

I claim:

The ornamental design for a food container or the like, as shown.
